IONIZATION OF GAS

Nils Torsten Johan Wilner, Stockholm, Sweden,
assignor, by mesne assignments, to Servel, Inc.,
New York, N. Y., a corporation of Delaware

Application June 30, 1937, Serial No. 151,314
In Germany July 9, 1936

19 Claims. (Cl. 175—265)

My invention relates to ionization of gas, especially air, by a suitable ion generator, and it is an object of the invention to control the generation and distribution of ions so that the ion content is automatically maintained substantially constant in a predetermined quantity and character.

It has been found that the ion content of air has certain physiological effects on the human body involving blood pressure and different other living functions. It has also been established that negative and positive ions have different effects and that there is a certain difference in the effects of ions of larger and smaller masses. The actions of ionized air indicate a definite optimum at which the effect of the ions is most favorable and it is therefore desirable to maintain the ion concentration in the air at this value.

The invention provides for automatic regulation of the ion content as described with particularity in the following description taken in connection with the accompanying drawings forming part of this specification and of which:

Fig. 1 shows more or less diagrammatically a device for producing ions;

Fig. 2 shows a detail of the device;

Fig. 3 shows more or less schematically a device for producing ions provided with automatic control; and

Figs. 4 to 7 inclusive show details and modifications of the control circuits.

The device shown in Fig. 1 consists of a box 10 where a blower or ventilator 11 is installed which sucks in the outside air through holes 12 provided in the walls of the box. The air stream delivered by the ventilator 11 is conducted through a pipe 13 which terminates in a second pipe 14 having a larger diameter than the pipe 13. The pipe 14 terminates at the right side wall of the box 10 at an opening covered by a screen 15 having streamlined bars 16. The grid 15 is preferably made of metal and conductively connected to the ground so that it forms a voltage protection. The ventilator 11 is driven by an electric motor, not shown, the contacts 17, 18 of which are conductively connected to contacts 19, 20 provided on the outside of the box 10. The primary winding 23 of a transformer 22 is also connected to these contacts 19, 20. A third contact 21, that preferably cannot be mistaken for the others, for example, by being given a different shape from the two contacts 19, 20, should be conductively connected to the ground. The transformer 22 has two secondary windings of which the winding 24 is connected to an incandescent body 25 that is to be maintained at emis-

sion temperature as well as to the ground conductor 32.

The incandescent body 25 may preferably be made of magnesium oxide, steatite, porcelain, or any other fireproof insulating material and designed as shown in Fig. 2. The insulating body 50 of the incandescent body has the shape of a cylinder and is provided with teeth 52 between which the heating wire 51 is wound. The heating wire consists preferably of platinum, chrome-nickel, or some other material which in the incandescent state still is sufficiently air resistant. The wire may, in order to generate ions at a comparatively low temperature, be coated with an oxide layer or some other material known to the science of incandescent cathodes. It is particularly appropriate to make the support for the incandescent wire of a material which itself emits ions as known to the art. This, for example, is the case with magnesium oxide. The heating body 25 is only supported by the bolt 26 and centrally disposed in relation to the pipes 13 and 14. A third pipe 30 is disposed between the cylindrical incandescent body 25 and the pipe 14 which serves as a radiation protection and which also is supported by the bolt 26. Centrally of the heating body 25 and the pipes 13, 14 and 30 there is provided an electrode 29 which is carried by a support 28. The support 28 as well as the electrode 29 is made of metal and insulated from the pipe 13 by a bushing 27 of insulating material.

The support 28 and the electrode 29 are connected by a wire 31 to one contact arm 42 of a two-pole switch, the other contact arm 41 being connected to one end of the secondary winding 40 of the transformer 22 by a wire 49. The contact arm 42 of the switch is also through a condenser 47 partly connected to the ground line 32, and partly by a wire 48 to the other end of the secondary winding 40. The two switch arms are moved simultaneously between two positions. In the one position shown in the drawing, the arm 41 is connected to the contact 43 which in turn is connected to a second contact 45 as well as also to one pole of a rectifier 46. The arm 42 of the switch is connected to a third contact 44 which is connected to the second pole of the rectifier 46. The rectifier 46 may preferably be a so-called contact rectifier, for example, a selenium rectifier, a cuprous oxide rectifier, or the like, but may also consist of an incandescent cathode rectifier. In the other switching position of the switch the contacts 41, 42 are connected reversely to the poles of the rectifier 46.

55 In the position of the switch shown in Fig. 1

the electrode 29 in the pipe 13 is negatively charged in relation to the ground, as the current flows from the line 48 through the ground line 32, incandescent wire 51, air space, electrode 29, line 31, switch arm 42, contact 44, rectifier 46, contact 43, switch arm 41, and the line 49. When the switch is reversed, that is, when the arm 41 is connected to the contact 44 and the arm 42 to the contact 45, the current flows in the opposite direction, that is, the electrode 29 becomes positive in relation to the ground. The incandescent body 25 thus becomes anode or cathode depending on the position of the switch. The purpose of the condenser 47 is to equalize the potential half-waves let through by the rectifier 46.

In other respects the device shown in Fig. 1 functions in the following manner: When the switch is in the position shown in the drawings, the electrode 29, as already mentioned, is negative in relation to the ground, that is, in relation to the incandescent body 25. The ventilator 11 forces an air stream through the pipe 13 that almost without any scattering continues its flow through the insulating pipe 30 of the incandescent body 25 toward the right and is led to the outside through the openings in the screen 15. As the incandescent body 25 is held at its emission temperature, both positive and negative ions are formed, the proportion of the two kinds of ions being dependent on the temperature of the incandescent body. When the electrode 29 is negatively charged in relation to the incandescent body 25, the positive ions are attracted and are thus imparted a velocity whose magnitude depends on the potential drop or the field intensity. On their way from the incandescent body 25 to the electrode 29 the ions are caught by the air stream and removed with it from the device. However, the air stream is only able to pull along ions whose velocity is not too great which particularly applies to ions having a greater mass. The ions having a smaller mass, for example, those that consist of a single molecule, can, if the field intensity is sufficiently great, attain such great velocity in the direction toward the electrode 29 that they are drawn along by the air stream only slightly from their path. They are, therefore, picked up by the electrode 29. Thus, the greater the field intensity, that is, the higher the potential maintained between the electrode 29 and the incandescent body 25, the greater will the velocities be of the ions of different sizes in the direction of the field. The air stream is then able to take along only the greatest ion masses while, on the other hand, when the aforesaid potential is low or the air velocity high, a larger number of ions having a smaller mass are carried away with the air. The air leaving through the screen 15, therefore, is charged with positive ions to an extent dependent on the temperature of the incandescent body, the potential between the incandescent body and the electrode 29 as well as on the velocity of the air stream. The masses of the ions pulled along by the air stream are, as mentioned, dependent on the potential between the electrode 29 and the incandescent body 25 as well as on the velocity of the air stream. Thus, there is on hand a control both for the total content of ions and also for their masses. These quantities must be chosen with regard to the desired action of the air since, as already mentioned, both these quantities as well as also the electrical symbol for the ion charge have different physiological actions on the human body.

By throwing the switch over, as mentioned before, the direction of the electrical field between the incandescent body 25 and the electrode 29 is reversed. Then the negative ions are attracted by the electrode 29 and, in the same manner as already described for the positive ions, caught by the air stream and removed from the plant.

Fig. 3 shows a device for improvement of air by regulation of its ion content to which along with an ion generator also is connected devices for regulating the air temperature comprising a unit aggregate. The designations correspond to those in Fig. 1. The box 10, which preferably consists of sheet metal, is designed as a piece of furniture like a cabinet in the upper part of which the ion generator is disposed together with the appertaining air transporting device. The outlet opening 15 for the improved air is also disposed in the upper part of the box 10. The box 10 itself is grounded by a line 21. The contacts 19 and 20 are disposed in the lower part of the box and are connected to a source of alternating current.

The contact 19 is connected to the primary winding of the transformer 22 through a line 60. The other end of the primary winding 23 is through a line 62 connected to a regulating device 64, shown schematically as a box, to be explained later. The contact 20 is through a line 61 also connected to the regulating device 64 which thus is connected between this contact 20 and the primary winding. The box 64 contains a transformer and rectifier, not shown, which on one side is connected to the ground and on the other through a line 63 to the electrode 29 of the ion generator.

The air to be improved is sucked in through an opening 67 disposed in the lower part of the box 10 and flows first through a cylindrical chamber 66 where there is disposed a sensing body 68 for the regulating device 64. The construction and operating method of this sensing body as well as the regulator 64 are explained more closely below. The sucked-in air continues to flow upwardly and sweeps over a radiator 74 of a refrigerating or heating source through the action of which the air is brought to the desired, preferably adjustable temperature as known to the art. The flow of air is caused mainly by a ventilator 70 which is disposed in an opening 79 in a partition 69 and driven by an electric motor 71 that is connected to the contacts 19, 20 by wires 73, 72 and wires 78, 60 respectively. The heating or refrigerating source 75 of the radiator 74 can be of any kind, for example, an electrical heating source or a compressor refrigerating apparatus or an absorption refrigerating apparatus as known to the art. It is recommended to construct the plant 74, 75 in such way that it can function alternately as heating and refrigerating source whereat the change from heat to cold and in the reverse order is effected by a single thermostatic arrangement. The sensing body of this thermostat is preferably disposed directly behind the inlet opening 67 so that the temperature of the inflowing air from the room is decisive for the action of the refrigerating or heating plant 74, 75.

The regulating device 64 controls the ion generator, that is, its ventilator 11 and heating body 25 in relation to the ion concentration of the air flowing through the plant. The control has for object to maintain the ion concentration of the air to be improved constant. When its ion con-

centration falls below a certain value, the device 64 is brought to function by means of the sensing body 68, as will be described later, and as the ventilator 11 and transformer 22 are connected, a new generation of ions is started. When the ion concentration of the air has reached a certain value, the current supply to the ventilator 11 and transformer 22 is disconnected automatically so that further ion generation automatically ceases. By means of a switching device similar to the switch device 41, 46 shown in Fig. 1 the device can be arranged for the generation of positive as well as negative ions.

Operation of the regulating device 64 can be induced by the variations in current between the sensing body 68 and the jacket 66 which is produced by the presence of ions in the air streaming in through the opening 67. But as the magnitude of the current even for a saturation current between the sensing body 68 and its surroundings, that is, in this case the jacket 66, is very small, an appreciable amplification of this current would, if so should be desired, be necessary by means of an electron tube, for example, an thyratron tube. Although it is possible in this way to obtain a safely operating and reliable regulating device, it is better in plants that are to be operated by laymen to provide a simpler device for this purpose. Instead, one utilizes for this purpose the variations in the potential of a condenser charged to a predetermined initial potential which is affected by the ion flow. The devices shown in Figs. 4 and 5 for regulating the ion concentration of the air comprise as an essential part two condensers that are charged to a predetermined potential, one of the condensers being discharged by the ion current while the other is discharged by a constant grid leak. The variations in the potentials of the condensers can be transformed into current variations in an electromagnetic switching circuit by means of electronic relays.

The regulating device according to Fig. 4 contains a source for direct current 120, which in the embodiment consists of a storage battery. However, it may consist of any suitable direct current generator and is in practice preferably replaced by an alternating current source, for example, a transformer winding with rectifier. The positive pole of the direct current source 120 is grounded. The negative pole is connected to a switching relay 115. After going through this relay the current flows to a switching relay, preferably polarized, which is provided with two excitation windings 121, 122. The windings of the relay are each connected to one of the two electron tubes 106 and 107, to be exact, each to one electrode 110 and 113. The second electrode 108, 111 of the electron tubes 106, 107 is grounded and thus connected to the positive pole of the direct current source. Thus there are two parallel circuits each containing an electron tube as well as each one of the magnet windings 121, 122 which are connected in series with the corresponding electron tube. The electron tubes 106, 107 may be of a kind known to the art, that is, consist of partly evacuated glass tubes containing a suitable gas, for example, argon or neon. Such so-called electronic relays are ignited by applying a definite potential between the main electrodes 110, 108 or 113, 111 whereby a current flows through the gas space of the corresponding tube.

The potential that is characteristic for the corresponding electronic relay and among other things dependent on the electrode spacing must

have a definite minimum value in order to effect ignition and thereby a passage of current. Once the tube is lighted, the discharge can continue even when the potential is lowered. A temporarily acting increase in the potential is, therefore, sufficient for the ignition as long as it corresponds to the ignition potential. However, it is known that this increase in potential can be replaced by an also temporarily acting auxiliary potential which is applied between one of the main electrodes and an ignition electrode provided between them. When the potential of the ignition electrode lies between the potentials of the main electrodes, as is the case in Fig. 4, ignition can, however, only take place when the potential of the ignition electrode lies in the neighborhood of the potential of one of the two main electrodes. This phenomenon is used in the plant according to Fig. 4 for the purpose of effecting the ignition of one or the other of the two electron tubes 106, 107 in relation to the potentials of two condensers 103 and 104. For this purpose the auxiliary electrode 112 is grounded through the condenser 104 in parallel connection to a high ohmic resistance 105, so that the condenser 104 can be charged through a switch 117 connected to a point of mean potential on the direct current source 120. The resistance may consist of a so-called radioactive leak. Such a leak contains as an essential part a gas discharge space which is under the influence of a radioactive material and thus always possessing a constant ionization of the gas. The charging of the condenser 104 takes place intermittently, that is, after the condenser has been charged to the potential existing between the ground and the connecting point 131 on the direct current source 120. Its connection with the direct current source is broken by lifting the switch 117.

It is now assumed that when the condenser 104 is being charged, the electron tube is not yet connected to the negative pole of the direct current source 120. Even when the condenser is connected to the aforesaid potential source and the total potential of the direct current source 120 at the same time is applied between the two main electrodes 113, 111 of the electron tube 107, the tube 107 is still not lighted because the potential of the ignition electrode 112 still lies between the potentials of the main electrodes. However, since the condenser 104, as mentioned, after being charged no longer is connected to the direct current source, its potential gradually sinks as its electric charge gradually is led away through the resistance 105. But the reduction in its charge also produces a decrease in the potential differential between the auxiliary electrode 112 and the main electrode 111, that is, the potential of the auxiliary electrode 112 approaches that of the main electrode 111. As soon as the potential differential has dropped to a definite value, the electron tube is lighted and current flows therethrough as well as through the winding 121 and the relay 115.

The second electronic relay 106 is in a similar manner connected to a condenser 103, preferably with a variable capacity. The auxiliary electrode 109 is, further, connected electrically to the sensing body 68 as shown in Fig. 4. The sensing body 68 and its surrounding jacket 66 correspond to the similarly designated parts in Fig. 3 and represent the leak corresponding to the resistance 105 for the electronic relay 107. A switch 116 is provided for the charging of the condenser 103 which is connected to the same

point 131 on the direct current source 120 as the switch 117. The charging of the condenser 103 takes place in similar manner to that already described for the condenser 104 and at the same time. The discharge of the condenser 103 takes place through the air, in the example, charged with positive ions, which, as described for Fig. 3, is sucked through the intermediate space between the sensing body 68 and the jacket 66. This ion current is, to be true, extremely weak but gradually effects a discharge of the condenser 103 so that the electronic relay 106 lights up. The potential between the sensing body 68 and the jacket 66 is preferably selected so high that there always exists a saturation current between the two electrodes at the prevailing ion content of the air. At saturation current the magnitude of the current is practically proportional to the ion content of the air flowing through. When the electronic relay 106 is lighted, a current is produced through the winding 122 and through the relay 115.

The electronic relay 107 as well as also the appertaining condenser 104 and the leak 105 represent to a certain degree a comparison unit with which the processes in the true ion regulator 106, 103, 66, 68 are compared. The two switches 116, 117 are actuated by the relay 115 so that the two condensers 103 and 104 through the impulses of the relay 115 temporarily are connected to the point 131 on the potential source 120 and thereby charged to the same potential. To make the drawing as clear as possible the connection between the relay 115 and the two switches 116, 117 is not shown. In practice, the relay 115, which may consist of an electromagnet with its appertaining armature, is mechanically connected to the switching organs of the two switches 116, 117. The armature of the relay 115 may by its movements effect the closing and opening of the contacts on the two switches 116, 117. The electromagnet of the relay 115 should be so connected to the direct current source 120 that current flows through it as soon as the two electron tubes light up.

The polarized relay 114 contains, as already mentioned, two windings 121, 122 which are connected in series with the electronic relays 107 and 106. An armature 125 is disposed between the two poles of the relay 114 which is pivotal and can be attracted by the one or the other of the two poles. The armature 125 is connected to a circuit consisting of a line 126, an electromagnet 129, a current source 128, and a line 127. When the armature 125 is in the position shown in the drawing, the aforesaid circuit is broken but when the armature is attracted by the magnet pole 121, the aforesaid circuit is closed. By this closing, the armature 130 is attracted, thus connecting the ion generator designated by 119 to the two alternating current contact points 19, 20. The armature 130 is held in its resting position by a spring 131 as soon as the winding of the electromagnet 129 does not carry any current. In the aforesaid position of the armature the energy supply to the ion generator 119 is broken. The relay 115 which is connected in the circuit for the two electron tubes 106, 107 contains further a device, not shown, for temporarily breaking the connection between the electron tubes and the direct current source 120 to effect the extinguishing of the electron tubes. This device will be disregarded for the present in order not to make the description of other complicated processes more difficult.

It will now be assumed that the two condensers 103, 104 have been charged to the same potential and that their connection to the point 131 on the direct current source subsequently has been broken. On the other hand, the two main electrodes 110, 108 and 113, 111 of the two electronic relays are constantly maintained under the potential of the aforesaid direct current source. The potential differential between the auxiliary electrode 109 or 112 and the corresponding main electrodes should not be so high that a discharge can be produced between the auxiliary electrode and the corresponding main electrodes. When this condition is fulfilled there is no discharge between the main electrodes of either of the two tubes 106, 107.

The charge of the condenser 104 is dissipated in shorter or longer time through the resistance 105 depending on the size of this resistance. The potential difference between the auxiliary electrode 112 and the main electrode 111 thus gradually is lowered and reaches in a definite time a value at which a discharge takes place in the electronic relay 107. Also, the condenser 103 is gradually discharged by the ions in the air flowing between the two electrodes 68, 66 of the sensing body. As the initial potential of the condenser 103 is the same as that of the condenser 104, any difference in the discharge times is dependent on the capacity of the variable condenser 103 and the true resistance of the gas space between the electrodes 66 and 68. For the same capacity of the two condensers 103, 104 the two electronic relays 106, 107 would light up at the same time. As a general rule the same would happen if the relation between the capacity of the condenser 104 and the resistance 105 equalled the relation between the capacity of the condenser 103 and the resistance of the aforesaid gas space. This, however, happens almost never in practice. In practice there will rather always be a difference in the ignition times of the two relays 106, 107. Which one of the two relays will be ignited first is dependent entirely on the magnitude of the resistance of the gas space 66, 68 when the capacities of the condensers 103, 104 and the resistance 105 are maintained constant.

The two electron tube systems 106 and 107 including the appertaining capacities and resistances are, however, as will be described later, so tuned in relation to each other that the discharge time of the condenser 104 corresponds to the desired ion content of the air. Therefore, if the condenser 103 is discharged faster than the condenser 104, that is, the relay 106 is lighted sooner than the relay 107, this indicates that the resistance of the gas space 66, 68 is too small, that is, that the ion content of the air has exceeded the desired value. But when the relay 106 lights up sooner than the relay 107, the magnet pole 122 of the switching device 114 is excited first and attracts the armature 125 so that this moves into the position shown in Fig. 4. As already mentioned, this has for effect that the circuit 127, 128, 129, 126 is broken and thereby the ion generator 119 shut off.

When, on the other hand, the ion content of the air is too small, that is, the resistance of the gas space 66, 68 is greater than normal, the potential of the auxiliary electrode 112 of the relay 107 drops faster than that of the electrode 109 so that the relay 107 lights up first. Then the current flows through the winding 121 and the armature 125 is attracted by this magnet.

Thus, in the manner already described, the ion generator 119 is started by changing the position of the contact 125.

The device according to Fig. 4 is designed for the regulation of positive ions, but may also by changing the direction of the electric field between the electrode 68 and the jacket 68 and by certain changes in the individual parts of the apparatus be used for the regulation of negative ions.

For this purpose it is only necessary to reverse the polarity of the direct current source 120. However, it has been found in practice that when the potential of the auxiliary electrodes 109, 112 is changed in a negative direction by the discharge of the two condensers 103, 104, a discharge between the auxiliary electrode and the positive main electrode (110, 113) may still take place. But this discharge does not effect the desired ignition of the complete relay, that is, it is not able to produce the discharge between the two main electrodes. It is therefore recommended to change the spacial arrangement of the main electrode and the auxiliary electrode as well as to provide a point on the negative main electrode.

By the changed spacial arrangement of the electrodes as shown in Fig. 5, the auxiliary electrodes 109, 112 are pointed and their points centrally disposed in a ring representing the negative main electrodes 108, 111. The two switches 116, 117 are connected to the point 131 on the direct current source to which the main electrodes 108, 111 also are connected. Thus, the last mentioned electrodes are not grounded as in Fig. 4 but are maintained at a potential positive in relation to the ground.

The method of operation of the device according to Fig. 5 differs from that of the device according to Fig. 4 only in regard to the ignition process. Both the main electrodes 108, 111 as well as the auxiliary electrodes 109, 112 are charged to the potential of the point 131. During the discharge process of the two condensers 103 and 104, the potential of the auxiliary electrodes 109, 112 sinks in the direction of the negative pole of the direct current source 120 while the potential difference between the auxiliary electrode and the positive electrode (110 or 113) increases to the ignition potential of the corresponding relay.

In view of the comparatively weak currents that flow through the magnet windings of the relay 114 it is recommended to construct this relay as a polarized relay as known to the art, for instance, by connecting the armature 125 magnetically to a permanent magnet which cooperates with the two ordinary magnetic circuits of the relay, as is usually done on the so-called telegraph relay. Corresponding measures may for the same reason also be taken for the relay 115.

As already mentioned, the relay 115 has two objects. It should first temporarily connect the condensers 103 and 104 to the point 131 on the direct current source 120 by actuating the two switches 116, 117. This charging should take place when the two electron tubes 106, 107 have been extinguished. The reason for this is that when an electron tube of this kind once has been lighted, the potential of its grid 109 or 112 has almost no effect on the magnitude of the current flowing through the electron tube. Therefore, the second object of the relay 115 is to extinguish the electron tube. For this purpose

the relay 115 must be so designed that it breaks up the supply of current from the direct current source 120 to the electron tubes 106, 107 as soon as the processes intended by the ignition of the relay have been completed. For this purpose the armature of the relay 115 has a resilient contact tongue, not shown, as known to the art, that can break the contact between the main electrodes 110 and 113 and the direct current source 10 120. The contacts of the relay 115 are so designed that the two switches 116, 117 remain in their closed positions until the connection of the two main electrodes 110 or 113 to the direct current source 120 has been closed after the extinguishing of the corresponding relay. Such a delay in the switching process of the two switches 116, 117 can be accomplished by different means known to relay art, the simplest being by resilient contacts. When one of the two tubes 106 or 107 is lighted (on account of a discharge of the corresponding condenser 103 or 104), a current flows through the appertaining magnet winding of the relay 114 and through the winding of the relay 115. The action of this current on the relay 114 has already been described. In relay 115 the following takes place:

The electromagnet of the relay 115 attracts its armature. By its movement in the direction toward the pole of the electromagnet the aforesaid contacts are displaced so that first the two switches 116 and 117 are closed so that the condensers 103 and 104 are charged to the starting potential, and then the connection of the electrodes 110 and 113 to the potential source 120 30 is broken. The electrode through which current has been flowing is hereby extinguished. The adjustment of the two relays 114 and 115 in relation to each other must be selected in such a way that the reversal of the contact 125 has been 35 finished before the armature of the relay 115 moves to the point of breaking the aforesaid circuit.

According as one or the other of the two electronic relays 106 or 107 is ignited, as mentioned 40 before, the ion generator 119 should be started or shut off. When the armature of the relay 115 has been pulled so far in the aforesaid direction that the connection between the upper pole of the direct current source 120 and the electron tubes 106, 107 has been broken, the armature moves, for example, under the influence of gravity or a spring, back to its resting position and then shortly after the ensuing reclosing of the main circuit does it break the connection of the 45 two condensers 103, 104 with the point 131. This order provides a safety measure against premature ignition of the tubes when the main potential again is applied. The selection of the particular embodiment of the switching devices must be made to suit the conditions and the type of 50 electron tube.

Fig. 6 shows schematically some details of the sensing body 68, 68 as well as its connection with the auxiliary electrode 109. The designations correspond to those in Fig. 4. In addition 132 designates the glass wall of the relay 106 at that point where the electrode 68 of the sensing body is carried through. To prevent an undesired creeping of the charges of the condenser 103 along different surfaces an annular jacket 133 is provided around the glass wall 132 of the electron tube 106. For the same reason a jacket 134 is provided between two annular insulating jackets 135, 136 which serves as insulation for 55 the electrode 68 against the outside grounded

jacket 66 of the sensing body, this latter jacket being designed as a screen. The two metal jackets 133 and 134 are connected electrically to the point 131 on the direct current source 120. These measures prevent, in a manner well known, any unintentional escape of the charges through creepage on the surfaces of the different apparatus parts.

The resistance 105 in Figs. 4 and 5 serving as a leak may be classified as a standard dissipator with which the dissipation of the charges of the condenser 103 through the ionized air is compared. According as the last mentioned dissipation has a magnitude at which the drop in potential of the condenser 103 down to the point where ignition of the relay 106 takes place sooner or later than the corresponding discharge of the condenser 104, the ion generator 119, as previously mentioned, will be disconnected or connected. The standard dissipator 105 as well as the appertaining condenser 104 should be so adjusted that the discharge of this condenser to the point of ignition of the relay 107 lasts just as long as the corresponding process in the relay 107 in the presence of an ion current between the electrodes 66 and 68 of the sensing body corresponding to the normally desired ion content of the air. When an ion concentration different from this standard ion content is desired, it is only necessary to set the variable condenser 103 for another capacity. By an adjustment of this kind the dissipation time of the condenser 103 is increased or decreased in comparison with the standard when the discharge time of the condenser 104 is maintained constant, depending on whether the capacity of the condenser 103 is increased or decreased. By an increase in the capacity, the start of the discharge is delayed so that the electron tube 107 is lighted first thus bringing the ion generator 119 into operation whereby the ion concentration of the air is increased. If the capacity of the condenser 103 is lessened, the discharge time of this condenser is shortened so that the ignition of the relay 106 takes place earlier than the relay 107 whereby the ion generation is shut off.

The regulating device according to Figs. 4 and 5 has, as mentioned before, for object to regulate the concentration of positive or negative ions or to maintain a constant concentration. Fig. 7 shows schematically a regulating device which regulates the ratio between the concentrations of positive and negative ions. The designations correspond to those in the preceding figures. The essential difference between the devices according to Figs. 4 and 5 on the one hand, and that of Fig. 7 on the other, lies in the fact that according to Fig. 7 the standard dissipator 105 of Figs. 4 and 5 has been replaced by a second sensing body whose electrodes are designated by reference numerals 266 and 268. The second sensing body should be sensitive to positive ions while the sensing body 66, 68 in this case is sensitive to negative ions. In accordance therewith the switch 117 for the relay 107 is connected to a contact point 231 on the direct current source 120 having a different polarity than the point 131. The two jackets 66 and 266 of the two sensing bodies as well as the electrode 111 of the relay 107 are grounded. Another difference from the devices in Figs. 4 and 5 is that none of the outside poles of the direct current source 120 is grounded. On the other hand the direct current source 120 has its middle point grounded. The minus pole 203 is connected to the electrode 113

of the relay 107. The contact point 231 for the switch 117 is now located between the grounded point 201 and the negative pole 203 of the direct current source 120. The positive pole 202 of the direct current source is, as in Fig. 5, connected to the electrode 110 of the relay 106. In order to make the drawing clear the switching relays 115 and 215 of the corresponding circuits of the electron tubes 106 and 107 are only shown schematically. The two relays have the same object as the relay 115 in Figs. 4 and 5 and can without difficulty be combined into a single relay whose electromagnet preferably is provided with two windings one of which is connected in the circuit 110, 122, 202 and the other in the circuit 113, 121, 203 so that the common relay is caused to function as soon as one of the two circuits carries a current. The joint connection of the two relays 115 and 215 or the operation of the common relay with the two switches 116, 117 can be accomplished in the same manner as in Figs. 4 and 5. The same applies to the devices for extinguishing the electron tubes.

The electromagnet 129 whose actuation is regulated in relation to the switch 125 in the already described manner has, according to Fig. 7, for object to effect a change in the direction of the current of the ion generator 119 and is, therefore, brought into operating connection with the switching device of the rectifier 46 (see also Fig. 1) by means of an armature 130. When the electromagnet 129 is excited by the operation of the switch 125, the armature 130 is attracted which in turn moves the two arms of the switch, that are pivotal around the points 241, 242, into a position at which the electrode 29 of the ion generator 119 is positively charged (in relation to the ground) whereby negative ions are discharged from the ion generator. When, on the other hand, the armature of the relay 125 has assumed the position shown in Fig. 7, that is, the electromagnet 129 is not excited, the position of the switch of the rectifier 46 is such that the electrode 29 of the ion generator 119 is negatively charged, thus causing the emission of positive ions.

Whether or not the relay 125 is closed or in open position is determined by the momentary content of positive or negative ions in the air.

In order to make the explanation clearer, the assumption is first made (which does not usually happen) that the content of negative and positive ions is the same. It is further assumed that the two condensers 103 and 104 have the same capacities. Then, when the concentration of negative ions becomes greater than that of the positive ions, the discharge of the condenser 103 to a point of ignition of the relay 106 takes place quicker than the corresponding process in the relay 107. This has for result that the relay 125 remains in a position for which the circuit 126, 129, 128, 127 remains broken. Due to this, the switch of the rectifier 46 remains in that position where the electrode 29 of the ion generator 119 receives a potential relative to the ground for which positive ions are emitted. For this reason the original ratio between the concentrations of the two kinds of ions is gradually reestablished.

A corresponding procedure now takes place when the concentration of positive ions becomes too great in relation to that of negative ions. Then the relay 107 is ignited earlier than the relay 106. The armature of the relay 125 is then thrown over closing the circuit 126, 129, 128, 127

which in turn produces a change in the position of the switch of the rectifier 46 in such way that the electrode 29 of the ion generator 119 receives a positive potential relative to the ground thus causing the emission of negative ions.

A surplus of one of the two kinds of ions is usually desired in practice. The maintenance of a surplus of ions of a certain kind is accomplished by setting the capacity of the variable condenser 103 a certain amount higher or lower in comparison to the capacity of the condenser 104 depending on whether a surplus of negative or positive ions is desired which, by way of example, may be different for hospitals, mass meetings, and the like.

The regulation of the device according to Fig. 7 of a relative amount of the ion concentration can be supplemented by a regulation of the absolute concentration.

The invention is not restricted to the shown embodiments. The ion generation can amongst other things be effected by any method of heating bodies of different compositions. The absolute amount of positive ions may be limited by an arrangement according to Fig. 4 and the amount of negative ions by an arrangement according to Fig. 5. The advantage of this arrangement is its automatic characteristics although the relation between the amounts of positive and negative ions must be predetermined. Or, for example, the absolute amounts of positive (or negative) ions can be determined by an arrangement according to Fig. 4 (Fig. 5) and the mutual relation of positive and negative ion content insured by an arrangement according to Fig. 7 in which case the throw-over switch 241, 242 in Fig. 7 is designed as a single switch which in one switching position allows the ion generator to produce only negative (positive) ions and in the other position breaks the circuit of the ion generator. Regulation of the absolute quantities of the ions to be generated within certain limits may further be attained especially in connection with Fig. 7 by regulating the heating source required for attaining the emission temperature or also by regulating the velocity of the air stream.

Other changes and modifications may be made within the scope of the invention which is not limited as shown in the drawings or described in the foregoing part of this specification but only as indicated in the following claims.

What is claimed is:

1. Apparatus for affecting the ion content of gas which includes an ion generator, electrostatic means for causing movement of ions from said generator into a stream of gas to be affected, means for controlling operation of said generator responsive to ion content of air to be affected, and means for controlling said electrostatic means to selectively cause movement of positive and negative ions from said generator into the gas stream.

2. Apparatus for affecting ion content of gas including an ion generator, a first path of flow for electricity, a second path of flow for electricity including gas to be affected, and means for controlling operation of said ion generator responsive to rate of flow of electricity through said second path relative to rate of flow of electricity through said first path.

3. Apparatus for affecting ion content of gas including an ion generator, means for controlling operation of said generator, means for causing flow of gas to be affected to said generator, and means for operating said control means re-

sponsive to the electrical conductivity of gas flowing to said generator.

4. Apparatus for affecting ion content of gas including an ion generator, two condensers, a fixed leak across one of said condensers, a leak across the other of said condensers comprising the gas to be affected, and means for controlling operation of said generator responsive to the differential in rates of discharge of said condensers through said leaks.

5. Apparatus for affecting ion content of gas including an ion generator, a fixed condenser, a variable condenser, a high resistance leak around said fixed condenser, a leak around said variable condenser including gas to be affected, and means for controlling operation of said ion generator responsive to the rate of discharge of said variable condenser with respect to rate of discharge of said fixed condenser.

6. Apparatus for affecting ion content of gas including an ion generator, an electromagnetic switch for controlling operation of said generator, two glow tube discharge relays for operating said switch, a starting circuit for one relay including a condenser and high resistance leak in parallel, a starting circuit for the other relay including a condenser in parallel with a leak including gas to be affected, and means for intermittently charging said condensers, said relay starting circuits being arranged so that the relay tube associated with the fastest leak lights first, and said relays being connected to said electromagnetic switch so that said ion generator is operated only when the relay tube associated with said high resistance leak lights first.

7. Apparatus for affecting ion content of gas including an ion generator, means for selectively causing movement of positive and negative ions from said generator, and means for controlling said first means responsive to the ratio of concentrations of positive and negative ions in gas to be affected.

8. Apparatus for affecting ion content of gas including an ion generator, means for selectively causing dispersion of positive and negative ions from said generator, two condensers, means for intermittently charging said condensers to the same potential and opposite polarity, a leak for each condenser including gas to be affected, and means for controlling said first means responsive to the differential in rates of leakage around said condensers.

9. Apparatus for affecting ion content of gas including an ion generator, means for selectively causing dispersion of positive and negative ions from said generator, two condensers of relatively variable capacities, means for intermittently charging said condensers to opposite potentials, a leak around each of said condensers including gas to be affected, and means for controlling said first means responsive to differential in rates of leakage around said condensers.

10. Apparatus for affecting ion content of gas including an ion generator, means for selectively causing dispersion of positive and negative ions from said generator, an electromagnetic switch for controlling said means, two electrical discharge tubes for controlling operation of said switch, a starting circuit for each tube including a condenser and a leak around the condenser consisting of gas to be affected, and means for intermittently charging said condensers.

11. A method of maintaining constant the ion content of gas which includes sensing the ion content of gas to be affected, generating ions, and

introducing the generated ions into gas to be affected responsive to variation of ion content determined by said sensing with respect to a desired content.

12. A method of affecting ion content of gas which includes measuring the relative positive and negative ion content of gas to be affected, generating ions, and selectively introducing positive and negative ions into gas to be affected according to the variation in ratio of positive to negative ion content of air to be affected as determined by said measurement with respect to a desired ratio.

13. In the art of affecting ion content of gas, that improvement which consists in creating two electrostatic fields, reducing one of said fields at a given rate, reducing the other of said fields at a rate dependent upon the ion content of gas to be affected, and generating ions and introducing the generated ions into air to be affected responsive to variation in the relation between said rates of electrostatic field reductions.

14. In the art of affecting ion content of gas, that improvement which consists in creating two electrostatic fields by opposite potentials, causing decrease in said fields by leakage through a path including gas to be affected, and generating ions and selectively dispersing positive and negative ions in gas to be affected responsive to variation in ratio of the rates of said electrostatic field reductions.

15. A method of affecting ion content of gas which includes generating ions, creating an electrostatic field to cause movement of ions away from the place of generation, picking up the ions so moved in a stream of gas to be affected, measuring the ratio of positive and negative ions in the gas to be affected, and changing the direction of said electrostatic field responsive to variation in said ratio to add positive or negative ions to the gas to maintain a desired ratio.

16. A method of maintaining constant the ion content of gas which includes comparing flow of electrical current through gas to be affected with flow of current through a determinate path and introducing ions into gas to be affected responsive to change in said comparison.

17. A method of conditioning air which includes measuring the ion content of air to be affected and selectively introducing positive and negative ions into the air in accordance with the ratio of positive to negative ion content as determined by said measurement to effect a desired ratio.

18. In a method of conditioning air with respect to its ion content, that improvement which consists in measuring the ion content of air to be affected, generating ions, creating an electrostatic field to cause movement of ions away from the place of generation, creating a stream of air to be affected through said electrostatic field to pick up ions, reversing said field to selectively move positive and negative ions into said air stream, and controlling said generation of ions responsive to said measurement of ion content of air to be affected.

19. A method of conditioning air with respect to ion content which includes sensing the ion content of air to be affected, generating ions, producing an electrostatic field to cause movement of ions away from the place of generation, producing a stream of air through said field to pick up ions, controlling said generation of ions responsive to said sensing to effect a desired ion content of the air, changing the direction of said electrostatic field to introduce into said air stream ions of a desired polarity, and varying the strength of said electrostatic field with respect to the rate of air flow to control the number and size of ion groups picked up by the air.

NILS TORSTEN JOHAN WILNER.
